UNITED STATES PATENT OFFICE.

CHARLES L. MOON AND JOHN ODELL, OF JOPLIN, MISSOURI, ASSIGNORS TO JOPLIN NOVELTY MANUFACTURING COMPANY, OF JOPLIN, MISSOURI.

PRINTING-MACHINE.

1,074,004.

Specification of Letters Patent. Patented Sept. 23, 1913.

Application filed August 6, 1912. Serial No. 713,602.

To all whom it may concern:

Be it known that we, CHARLES L. MOON and JOHN ODELL, citizens of the United States, residing at Joplin, in the county of Jasper 5 and State of Missouri, have invented new and useful Improvements in Printing-Machines, of which the following is a specification.

This invention relates to a machine for 10 printing strips or tapes of paper, fabric or other suitable material for advertising or other purposes, the primary object of the invention being to provide a simple, reliable and efficient machine whereby the operation of printing one or more strips may be readily, conveniently, cheaply and expeditiously carried out.

A further object of the invention is to 20 provide a machine of this character which will take the strip from a roll and rapidly print and rewind the same in roll form, and which permits of interchangeable parts being used, whereby strips of any width may be printed.

25 The invention consists of the features of construction, combination and arrangement of parts, hereinafter fully described and claimed, reference being had to the accompanying drawings, in which:—

30 Figure 1 is a side elevation of a printing machine embodying our invention. Fig. 2 is a top plan view of the same. Fig. 3 is an end view of the printing mechanism, *per se*, parts appearing in section. Fig. 4 is a 35 vertical transverse section of the supply device. Fig. 5 is a similar view of the rewinding device. Figs. 6 and 7 are, respectively, a side view of the guide, and a plan view of the guide roll removed from its supporting standards.

40 The apparatus comprises a printing mechanism proper A, a supporting or supply device B, upon which the strips or tapes are carried in roll form, and a rewinding device 45 C on which the strips or tapes are again rewound into roll form after passing through and being operated upon by the printing mechanism. These three parts of the apparatus may be mounted upon a bench, table 50 or other suitable support D.

The printing mechanism A consists of a 55 frame structure including a base or bottom cross bar 1, standards or uprights 2, and an upper cross bar 3, said standards being provided with vertical longitudinal bearing slots

4 communicating at their upper ends with lateral slots 5, each of which extends through one of the side edges of its standard. The upper cross bar 3 supports a series of ink reservoirs or fountains 6, equal in 60 number to the sets of printing rolls, and each provided with a discharge nozzle 7 having a controlling valve 8. Arranged within the base of said frame structure of the printing mechanism is a series of platen rolls 9, equal in number to the strips or 65 tapes to be printed at a time, which rolls are fixedly mounted upon a transverse shaft 10 journaled in bearing openings 11 in the lower ends of the standards. Above the 70 rolls 9 is arranged a corresponding series of printing rolls 12, carrying removable and interchangeable printing forms 13, which may be in the form of plates, stamps or set-up type, as desired, and are suitably 75 constructed and arranged so as to be removably secured in position for use, so that the type forms may be changed whenever desired according to the subject matter to be printed. These rollers and forms may 80 be constructed and arranged to print a tape or strip of any given width, or strips of different widths. The said rollers 12 are journaled loosely upon a shaft 14 for free 85 revoluble movement, the ends of which shaft are of angular form and fit within the slots 4.

Arranged within the upper portion of the frame are inking rolls 15 which are adapted to be supplied with ink from the nozzles 7 of the superposed ink reservoir 6 and are mounted to revolve upon a transverse shaft 16 having angular ends fitting within the slots 4, as shown. Below the inking rolls, and between the same and the printing rolls 12, are inking distributing rolls 17, which 95 receive the ink from the rolls 15 and distribute the same uniformly and evenly to the printing forms upon the rolls 12. These rolls 17 are mounted upon a transverse shaft 18 also having angular ends fitting within the slots 4. It will thus be seen that all three sets of rolls 12, 15 and 17 are loosely mounted upon their respective shafts, which are removably mounted within the slots 4, and may be inserted therein and removed therefrom through the slots 5, thus enabling said sets of rolls to be removed, so that the number of sets of printing couples may be varied as desired, for the printing of any suitable num- 110

ber of tapes or strips at a time within the limits of the width of the frame. By thus removably mounting the rolls 12, 15 and 17 they are adapted to be readily and conveniently cleaned, repaired or replaced whenever desired. Spacing disks or washers 19 are mounted upon the respective shafts to adapt the rolls of each set to run truly and to also space them the required distance apart. Preferably the rolls 9 are of maximum width, while interchangeable rolls 12, 15 and 17 of various widths are employed, so that type forms of different widths may be used or the number of printing, inking and ink distributing rolls varied for use in conjunction with a single set of platen rolls, to print a greater or less number of tapes or strips in a single operation. Coiled springs 20 have upper hooked ends engaging the projecting ends of the shaft 16 and lower hooked ends engaging pins or studs 21 on the standards, which springs exert their contractile energy to maintain any desired tension on the rolls and strips or tapes. The pins or studs 21 are adjustably engaged with the standards, whereby the resistance and tension of the springs may be varied.

The tapes or strips 21^a are mounted in roll form upon a corresponding number of grooved drums or pulleys 22 constituting a part of the supporting or supply device B. These drums are separated by washers or spacing devices 23, and are mounted to revolve freely on an axle bolt 24 carried by a pair of supporting standards 25 and 26. The standard 25 has an opening 27 through which the headed end of the bolt extends, while the standard 26 has a threaded socket 28 receiving the opposite threaded end 29 of the axle bolt. Engaging this threaded end of the bolt is a nut 30, and surrounding said bolt between the nut and the adjacent drum is a coiled spring 31 adapted to be tensioned by said nut, whereby the drums will be held to turn with any desired degree of freedom. It will be understood, of course, that this construction adapts the shaft and drums to be readily applied and removed, so that drums of different sizes may be employed, or the number of drums varied according to the number of tapes or strips to be simultaneously printed. The tapes running from the drums 22 to and between the rolls 9 and 12 pass beneath a tensioning and guide roller 32. This roll comprises a core or central section 33 mounted upon a shaft 34 having threaded ends 35 engaging openings in supporting standards 36 and receiving pairs of clamping nuts 37 whereby it is adjustably and removably secured in position. Carried by the body or core section 33 of the roll are adjustable outer or peripheral sections 37^a connected with the core section by adjusting screws or

bolts 38 carrying nuts 39 and springs 40, whereby the diameter of said roll may be varied as circumstances may require in guiding the strips or tapes to the space between the meeting faces of the rolls 9 and 12 and maintaining said strips or tapes at a desired tension while they are being printed.

It will be understood from the foregoing description that in the operation of the parts so far described, the strips or tapes from the rolls on the drums 22 are passed between the printing couples 9 and 12 and fed by the motion of the latter therethrough, whereby said strips or tapes are simultaneously and continuously printed in the operation of the machine, the tension of the feeding strips being regulated by the action of the tensioning and guide roller 32 and the freedom of revolution of the drums 22, which may be regulated by means of the nut 30 and spring 31, the pressure of the printing rollers on the platen rollers and strips or tapes being maintained and regulated by means of the springs 20. It will, of course, be understood that in the printing operation the individual strips or tapes may be printed in the same or different colors, and also have imprinted thereon the same or different subject matter. It will be apparent that by this construction of the printing and supply mechanisms, any desired number of rolls of tapes or strips within certain limits and of different lengths may be easily, conveniently and rapidly printed.

The printed tapes pass from the printing rolls to a series of receiving rolls 41 constituting a part of the rewinding device C. These rolls are in the form of flanged or grooved drums or pulleys, similar to the drums or pulleys 22, and are mounted to revolve with desired freedom upon a transverse shaft 42 and held in a desired spaced relation by spacing disks or washers 43. The shaft is journaled at one end in a bearing 44 on a supporting standard 45, and provided at such end with a band wheel or pulley 46, by which it may be driven by a belt from any suitable source of power. The other end 47 of the shaft is threaded and provided with a detachable journal 48 engaging a bearing slot or opening 49 in a standard 50, by which the shaft and drums are removably mounted in position, so that different sizes or widths of drums may be employed, or the drums varied in accordance with the number of supply drums and printing couples employed. Engaging the threaded end of the shaft is a clamping nut 51 which bears against an adjacent disk or washer and holds the drums assembled to rotate with the desired freedom. In the operation of printing the tapes, the ends of the tapes are led from the supply drums between the printing rolls and platen rolls and suitably connected with the receiving or

rewinding drums 41, under the pull of which the tapes or strips are fed through the printing mechanism and from the supply drums and after being printed are rewound upon 5 the rewinding drums, from which they may be bodily removed in an obvious manner and mounted upon spools for storage, sale or use. The drums or spools 41, of course, may constitute the holding drums or spools upon 10 which the rolls are mounted for service, which drums may be removed from the driving shaft after the strips are printed and new drums substituted therefor.

In practice, the printing forms upon the 15 printing rollers may consist of rubber plates or strips bearing the desired type faces or matter to be printed, and these strips may be secured in place in any preferred manner, so that they may be removed and new strips 20 substituted therefor with or without requiring detachment of the printing rolls. When the machine is in operation, the valves 8 are, of course, adjusted to feed the required amount of ink by gravity to the inking rolls 25 15, from which the ink is spread over the rolls 17 for distribution to the printing rolls.

The apparatus will be found of advantage in printing strips or tapes for advertising or other purposes, where rapidity of action and 30 economy of operation are factors of importance.

We claim:—

1. In an apparatus of the character described, in combination with strip supplying 35 and winding devices, a printing mechanism including a frame, a plurality of platen rolls

journaled in said frame, a series of sets of printing, ink distributing and inking rolls independently mounted upon shafts arranged in regular order above the platen 40 rolls and slidably connected with and removably mounted upon the frame, tensioning springs disposed between the frame and shaft of the inking roll for maintaining the sets of rolls in contactual relation, means for 45 supplying ink to the respective inking rolls, and suitable driving mechanism for the winding devices.

2. In an apparatus of the character described, and in combination with strip supplying 50 and winding devices, a printing mechanism including a frame having vertical slots with lateral entrances, a plurality of platen rolls journaled in said frame, a series of sets of printing, ink distributing 55 and inking rolls independently mounted upon shafts fitted within said slots in regular order above the platen rolls, tensioning springs connected with the frame and shaft of the inking roll for maintaining the sets of 60 rolls in contactual relation, means for supplying ink to the respective inking rolls, and suitable driving mechanism for the winding devices.

In testimony whereof we affix our signatures in presence of two witnesses.

CHARLES L. MOON.
JOHN ODELL.
